UNITED STATES PATENT OFFICE.

NATHANIEL LOMBARD, OF WORCESTER, MASSACHUSETTS, ASSIGNOR TO LOMBARD CARBURETER COMPANY, OF WORCESTER, MASSACHUSETTS, A CORPORATION OF MASSACHUSETTS.

CARBURETOR.

Application filed July 11, 1924, Serial No. 725,500. Renewed December 17, 1927.

My invention relates to carburetors for use with internal combustion engines and the like to form the explosive mixture of air and fuel used therein. The object of my 5 invention is to produce an improved form of carburetor adapted to control the flow of fuel from the main supply tank to the engine, without the use of a pump or equivalent, so that the mixture at the engine 10 intake manifold for any given condition of load, throttle position and engine speed, will be practically constant, irrespective of the level of the main fuel supply in relation to the carburetor, within reasonable limits. 15 More specifically, I have found that when my improved carburetor is properly adjusted with the engine running, the main fuel tank may be taken and raised above the level of the carburetor as much as two 20 feet, or lowered below the level of the carburetor as much as six or seven feet, and the engine will continue at the same speed and develop the same horsepower. It is possible to make such a test by using a flexible 25 pipe.

Thus my carburetor is particularly adapted for aeroplane engines, and automobile engines, with the gasoline tank at the rear, if desired, no pump or vacuum tank 30 being necessary, and the automobile engine will operate on the steepest hill met with the same efficiency as on the level.

This application is a continuation, in part at least, of my copending application Serial 35 No. 656,774, filed Aug. 11, 1923, and in a divisional application Serial No. 69,422, filed November 16, 1925, I claim certain combinations herein described, the claims of the present application being confined to the 40 supply chamber, the bellows, valve device and associated parts.

The above and other advantageous features of my invention will hereinafter more fully appear, reference being had to the accompanying drawings, in which—

Fig. 1 is a vertical sectional view of a carburetor embodying my invention.

Fig. 2 is a horizontal sectional view along the line 2—2 of Fig. 1, looking in the direction of the arrows.

Fig. 3 is a horizontal sectional view along the line 3—3 of Fig. 1, looking in the direction of the arrows.

Like reference characters refer to like parts in the different figures.

Referring to Fig. 1, the casing or shell of the carburetor is generally indicated at 1 and provides the usual flange 2 to facilitate its attachment to the intake manifold of the engine, not shown. Air enters the carburetor at 3 and passes through a Venturi passage 4, on its way to the engine. I show the usual throttle valve at 6. A hollow cylindrical valve casing 7 is secured to the shell 1 below the air chamber 3, within which fits a hollow piston 8. The piston 8 is provided with a reduced portion 9 slidable within a sleeve 10 extending upwardly from the casing 7. The reduced portion 9 of the piston terminates in a tapering or ogee portion 11, around which a collar 12 tightly fits, and the latter seats in the throat of the Venturi passage. The parts 11 and 12, by their form, materially heighten the Venturi effect when they are slightly withdrawn from the throat. A coiled spring 13 is received within the portion 9 of the piston 8, and is seated at its lower end on a plate 14 closing the lower end of the valve casing 7, whereby the pressure of the spring 13 tends to maintain the piston 8 and the tapering portion 11 and collar 12 in the position shown in Fig. 1.

The valve portion 11 is provided with a central opening 15, within which is slidably received a valve stem 16 extending downwardly from a boss 17 located at the top of the shell 1. The lower end of the stem 16 forms a needle valve proper 18, which extends into the constricted opening 19 of a tube 20 carried by the tapering portion 11. Above the tube 20 is a space 21 in the tapering portion, and this space is connected to the Venturi passage by means of a member of radial and axial passages 22 formed by drilling the tapering portion 11 and grooving its sides before the collar 12 is fitted on.

The tube 20 extends downwardly into a sleeve 23 projecting upwardly from the plate 14, and the lower end of tube 20 carries a piston 24, which is slidable within a hollow cylindrical casing 25 which extends below the plate 14. It will be apparent that the parts 8, 9, 11, 12, 20 and 24 are attached together as a unit, and when they move they move as such.

The end of the casing 25 is closed by a plate 26 which is provided with a central opening 27, normally closed by a check valve 28. The plate 26 is also provided with passages 29 extending radially from the opening 27, which passages 29 communicate with passages 30 extending upwardly through the walls of the casing 25, whereby the small space 31 above the top of the piston 24 is in communication with the opening 27. The space 31 is also in communication with the interior of the tube 20 through a restricted passage 32 provided in the wall of the tube 20, for a purpose to be hereinafter described.

The tapering portion 11 is also grooved to provide a number of axial passages 33 between it and the collar 12, as in the case of axial passages 22, but the two sets of passages are not intercommunicating. The passages 33 connect the Venturi passage 4 with the interior of the hollow piston 8 and the chamber inclosed within the casing 7. Figure 2 shows the relative arrangement of passages 22 and 33. The space 34 above the piston 8 is in communication with the outside atmospheric pressure, in any suitable manner, such as a groove along the portion 9, or a hole through the horizontal portion of the sleeve 10 at 34^a.

When a suction is created by the engine, the interior of the piston 8 will be subjected to this suction, it being communicated by the passages 33, whereupon the piston 8 will move downwardly against the force of the spring 13. Such downward movement will allow a draft of air, entering at 3, to go through the venturi 4 to the engine, and at the same time, the needle valve proper 18 and the tube 20 having been separated, fuel is sucked through the passages 22 and mixes with the air.

It will be noted that the passages 22 open into the venturi 4 practically at the point of maximum air velocity, and the suction thus created will lift fuel from a tank several feet below this point. In the use of my improved carburetor with automobile engines, it is not sufficient, however, merely to lift the fuel, but the flow thereof must be controlled and regulated, and by my invention I have provided means for regulating the flow that is essentially dynamic in its action, so that the results hereinbefore mentioned may be achieved.

Proceeding with the description of parts, the plate 26 provides a nipple 35 having an opening 36 in communication with the opening 27, and the nipple 35 is surrounded by a coupling 37 having a passage 38 extending therethrough, in communication with the nipple opening 36. The coupling 37 provides a cup-shaped portion 39, into which the passage 38 opens, and the portion 39 serves as a base for a shell 40, thereby pro-

viding an inclosed chamber 41 in direct communication with the opening 27 in the bottom plate 26 of the carburetor. An expandible diaphragm bellows device 42 is located within the shell 40. The upper end of the bellows 42 is carried by a nipple 43 in threaded engagement with a nut 44 secured to the top of the shell 40, a lock nut 45 cooperating with the nipple 43. The nipple 43 has a passage 46, and I desirably provide a cap 47 with an air vent 48 to keep dirt out of the bellows diaphragm 42.

The free end of the bellows 42 is provided with a concave seat 49 which, in the position of parts as shown, is just out of contact with a ball 50 provided at the upper end of a valve stem 51. The valve stem 51 extends downwardly into air opening 52 provided in the coupling 37, the stem 51 being provided at its lower end with a valve 53. The valve stem 51 is carried by a spring 54 just below the ball 50 which, when the engine is not running, serves to maintain the valve 53 in engagement with a seat 55, thereby closing the opening 52. That portion of the opening 52 below the valve seat 55 is connected by a pipe 56 to a supply tank 57, only a portion of which is shown. In the operation of the improved carburetor, the needle valve mechanism described opens more or less in response to the extent of suction created by the engine, the needle valve mechanism being very sensitive on account of the venturi and the action of the piston 8. However, the said needle valve mechanism will not respond separately to each stroke of the engine on account of the damping action of the piston 24. If, however, an engine with six or more cylinders is equipped with the carburetor of the present invention, this damping piston may be dispensed with.

The needle valve mechanism responsive to engine suction cooperates with the diaphragm controlled valve 53 to allow a given quantity of fuel per unit of time to be consumed by the engine for a given engine speed and setting of the throttle 6, in other words, for a given suction, irrespective of the exact "head" of fuel between the surface of fuel in tank 57 and the valve 53 (within reasonably wide limits) for the following reason:

If the said "head" is diminished for any cause, the diaphragm 42, which responds to a differential between this "head" considered statically and the effective suction on the needle valve mechanism, closes the valve 53 slightly. The frictional effect is then increased at the valve 53, and on account of the direction in which said valve faces, this frictional effect tends to close the valve 53 still further. This may be properly called a dynamic effect, and the result is that whatever the exact height of the fuel in the tank 57, the aforesaid static and dynamic forces

combine with the action of the needle valve mechanism to perfectly control the supply of fuel.

Additional features of the invention reside 5 in the fact that the stem 51 is held rigidly as far as sideways motion is concerned, and will not partake of any vibration in a horizontal plane induced by the diaphragm 42, owing to the separation between the seat and 10 ball 49 and 50.

Also it will be noted that if for any cause the chamber 41 should become flooded, the diaphragm 42 would immediately collapse, owing to the hydrostatic action of the fuel, 15 and prevent further fuel entering the chamber 41 until the level had been lowered. This action is however, usually induced before the actual touching of the diaphragm 42 by the fuel, owing to a compression of air 20 within said chamber 41. The fact that very little fuel is kept, at any time, in the chamber 41, renders the carburetor exceptionally safe from the standpoint of fire hazard.

It may be observed that statically considered 25 there would seem to be no reason why fuel should ever rise into the chamber 41, but the flow past the valve 53 is sufficient in velocity to cause it to rise; at any rate actual experiment shows that it does so rise during 30 operation normally to about the lower dotted line position in Fig. 1, while under unusual conditions, it has been observed to rise as far as the upper dotted line position.

Having thus given an illustrative embodiment 35 of my invention together with the result achieved which is, so far as I am aware, new, and surely highly useful, and having attempted an explanation of the physical laws which coact with the means shown to 40 effect the desired result, it must be understood that the correctness of the said explanation is not guaranteed, but seems to me plausible, while the result has been proved by experiment, and the means is clearly 45 shown and described. Therefore, I do not wish to be limited to the particular form of the invention herein shown, the scope of my invention being properly set forth in the appended claims.

50 I claim:

1. In a carburetor, a supply chamber for liquid fuel, a valve for controlling the admission of fuel to said chamber, a flat spring in a plane substantially perpendicular to the 55 movement of said valve for holding said valve in its closed position and for substantially preventing sidewise vibration of said

valve, and an expansible diaphragm located within said chamber, said diaphragm being provided with a seat adapted to engage a 60 portion of said valve upon downward movement of the diaphragm, thereby also substantially preventing sidewise movement of said diaphragm when the seat and valve are in engagement. 65

2. In a carburetor, a fuel supply chamber open to admit and discharge fuel only at the bottom, an expansible bellows device in said chamber adapted to expand in response to decrease of gaseous pressure in said chamber, the interior of said bellows device being open to the atmosphere, and a valve device 70 for admitting liquid fuel to said chamber operatively connected to said bellows and adapted to be opened upon expansion of said bellows, the parts being so arranged that upon the fuel in said chamber reaching a predetermined level the hydrostatic pressure 75 thereof operates to contact said bellows and close said valve device, thus keeping a minimum of fuel in said chamber. 80

3. In a carburetor, a fuel supply chamber, an entrance orifice for said chamber, an exit orifice for said chamber, both orifices being at a low point in said chamber, an expansible pneumatic device, the interior of which is open to the atmosphere, in said chamber, a valve controlling entrance of liquid at said entrance orifice under the control of said pneumatic device, whereby expansion of the latter opens said valve and contraction closes it, said pneumatic device having a surface at a low point in said chamber whereby upon the liquid reaching a predetermined low point in said chamber it 95 acts hydrostatically on said pneumatic device to close said valve. 90

4. In a carburetor, a supply chamber for liquid fuel, an expansible bellows device rigidly attached to the top of said chamber, a valve in the lower part of said chamber, guiding means holding said valve from vibration, and concave and convex surfaces, one carried by the lower part of said bellows, the other carried by said valve, whereby the lower part of the bellows is held from sideways vibration by the means guiding said valve, and whereby said bellows, on expansion, pushes said valve downwardly, thus opening it, said valve and said bellows, when the latter is contracted, being unconnected. 100 105 110

Dated this third day of July, 1924.

NATHANIEL LOMBARD.

CERTIFICATE OF CORRECTION.

Patent No. 1,693,793.

Granted December 4, 1928, to

NATHANIEL LOMBARD.

It is hereby certified that error appears in the printed specification of the above numbered patent requiring correction as follows: Page 3, line 79, claim 2, for the word "contact" read "contract"; and that the said Letters Patent should be read with this correction therein that the same may conform to the record of the case in the Patent Office.

Signed and sealed this 8th day of January, A. D. 1929.
